(57) **CLAIM**

I claim, the ornamental design for a car seat for pets, as shown and described.

DESCRIPTION

FIG. 1 a perspective view of a car seat for pets showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top plan view thereof showing the car seat for pets in an open configuration; and,

FIG. 9 is a reference view showing a configuration of use with a cushion.

The broken lines shown in FIGS. 1–9 on the surface of the car seat for pets are illustrative of stitching and do form a part of the claimed design. All other broken lines, including the dot-dash lines shown in FIG. 9, illustrate environmental structure and form no part of the claimed design.
